UNITED STATES PATENT OFFICE.

DAVID OPPENHEIM, OF NEW YORK, N. Y.

DESIGN FOR A BARBER'S CHAIR FOR CHILDREN.

54,764.

Specification for Design.

Patented Mar. 23, 1920.

Application filed September 19, 1919. Serial No. 325,031. Term of patent 14 years.

To all whom it may concern:

Be it known that I, DAVID OPPENHEIM, a citizen of the United States, residing at the city, county, and State of New York, have invented a new, original, and ornamental Design for a Barber's Chair for Children, of which the following is a specification, reference being had to the accompanying drawing, forming part thereof.

The figure is a perspective view of a barber's chair for children showing my new design.

I claim:

The ornamental design for a barber's chair for children, as shown.

DAVID OPPENHEIM.
